UNITED STATES PATENT OFFICE.

ERNA M. STEPKE, OF DETROIT, MICHIGAN.

CHILD'S SANITARY BED-SWING.

1,376,476.

Specification of Letters Patent.

Patented May 3, 1921.

Application filed December 31, 1919. Serial No. 348,621.

To all whom it may concern:

Be it known that I, ERNA M. STEPKE, a citizen of the United States of America, residing at Detroit, in the county of Wayne 5 and State of Michigan, have invented certain new and useful Improvements in Children's Sanitary Bed-Swings, of which the following is a specification, reference being had therein to the accompanying 10 drawings.

This invention relates to children's hammocks, swings or suspended beds and its object is to provide a simple construction which may be collapsed and folded into a 15 small bundle and will be light, sanitary and cheap to manufacture. A further object of the invention is to construct a device of this character that the child occupying the same will rest upon or be supported by a fabric body independently of the frame of the device so that the child cannot be caused 20 discomfiture by resting upon an unyielding or rigid frame but will rest upon the fabric alone which is carried by the frame in such a manner as to preclude possibility of 25 the child being caused discomfiture by being supported directly by the frame.

It is also an object of the invention to provide a new and novel frame construction 30 which is very light, durable and may be easily taken apart for the purpose of collapsing it into a small space to facilitate carrying the device about.

It is also an object of the invention to so 35 construct the fabric body that it may be folded into a compact bundle and so that the frame for holding the body extended may be quickly and easily detached therefrom and the fabric body cleansed to make it sanitary. 40 It is also an object of the invention to provide certain new and useful features in the construction and arrangement of parts all as hereinafter more fully described.

With the above and other ends in view, 45 the invention consists in the matters herein-after set forth and more particularly pointed out in the appended claims, reference being had to the accompanying drawing in which

Figure 1 is a perspective view of a device 50 illustrative of the invention showing the same in condition for use;

Fig. 2 is a transverse vertical section through the same;

Fig. 3 is a plan view of a rectangular 55 frame;

Fig. 4 is a sectional detail of a corner member of the frame;

Fig. 5 is a sectional detail of a slip joint of a side member of the frame, and

Fig. 6 is a small diagrammatic view of a 60 fabric body illustrating the manner in which the same is adapted to be folded.

As shown in the drawing, 1 indicates a rectangular fabric body as a whole, said body comprising a strip of fabric forming the 65 two longitudinal sides 2, 2, and the bottom 3 of the body, and the ends 4 comprising strips or pieces of fabric attached at 5 to the end edges of the sides 2 along the corners of the body and to the end edges of the bottom 70 3 along the end corners 6 of the body. The strip forming the sides 2 and bottom 3 is folded upon itself at each end to form hems 7 along the upper side edges 8 of the sides 2, which hems 7 are open at each end, and 75 this strip is also folded upon itself to form hems 9 along the bottom side corners of the body, and the fabric stitched together to form the meeting angle or corners 10 of the sides 2 and bottom 3, said hems 9 being 80 also open at their ends at the vertical corners 5 of the body. The fabric forming the ends 4 of the body is also folded upon itself to form hems 11 along the upper edges and in a like manner folded upon itself to form 85 hems 12 along the lower edges of the ends, the fabric being stitched along the meeting angle of the ends and bottom, or corners 6 to hold said ends to the bottom and to also 90 hold the folded portions of the fabric forming the hems 12.

Straps, by means of which the body may be suspended, are formed of fabric or other suitable material and comprise angle pieces 13 which are stitched at 14 to the inner side 95 of the hems 11 adjacent each corner 5 of the body and converge upwardly and are secured together at 15 and to the ends of a strip 16 which is provided intermediate its ends with a loop 17 engaging and holding 100 a ring 18 by means of which the entire device may be suspended.

To hold the body 1 extended, top and bottom frames indicated as a whole at 19, are provided to engage the hems 7 and 11 extending along the upper edges of the body and the hems 9 and 12 extending along the lower angles of the body. These frames 19, which in assembled condition are each substantially rectangular in plan view and of 110

greater length and width than the length and width of the fabric body, comprises side members 20 and 21 which are preferably thin metal tubes with their adjacent ends 5 formed to telescope one within the other and provided with annular grooves or depressions 22 as illustrated in Fig. 5, adapted to interlock when the ends of the tubes are slipped together and hold said tubes against 10 relative longitudinal movement, the end of the inner member 21 being slotted, as shown at 23, to permit it to yield in passing the internal rib formed by the groove or depression 22 in the outer member.

15 The ends of the frames 19 also preferably comprise light tubular members 24 and the ends of these members 24 and the adjacent ends of the side members 20 and 21 are preferably formed with annular grooves or de- 20 pressions 25 forming internal ribs on said members to engage and interlock with similar grooves on the ends of the tubular corner members 26, as shown in Fig. 4, the ends of said corner members 26 being split longitudinally as at 27, if found desirable, to 25 permit these ends to yield when forced into the ends of the side and end members of the frame. Each frame 19 is therefore made up of a series of light tubular sections 30 which may be quickly and easily disconnected one from the other, and the whole frame made into a compact bundle which may be folded inside of the fabric body when said body is folded, as hereinafter de- 35 scribed.

Obviously, these frames may be constructed of other material than tubing and the jointed connections of the several sections may be made in any suitable manner. 40 Also the corner members of the frame may be made of tubing, as shown, or may be constructed in any other suitable manner to connect the side and end members and permit them to be detachably connected together or 45 folded one upon the other.

The construction of the fabric body is such that it may be quickly and neatly folded into a very small, compact bundle, such manner of folding being illustrated in 50 Fig. 6 wherein the ends 4 are folded inwardly upon the bottom 3, the attached end portions of the sides 2 being folded inwardly upon said sides which are first folded outwardly from the sides of the bottom. 55 After the ends are so folded inwardly, the sides 2 in their partially folded condition are then folded over upon the inturned ends, as indicated by the dotted lines 28, the sides 2 and ends 4 thus being caused to lie flat 60 upon the bottom 3 in superposed relation and within the area of said bottom, with the attached suspending strap covered by the folded over side portions. The folding of the body is guided by the connecting seams 65 of the corners of the body so that said body

may be quickly, neatly and compactly folded so that it may be rolled up into a very small bundle with the rod sections forming the frames 19 contained within the bundle, which bundle will form a small, neat package that may be easily carried about and the device unfolded and extended for use wherever needed.

The body being formed entirely of a washable fabric and the frames being removable therefrom, a very sanitary device is provided and as the frames are of greater length and width than the length and width of the fabric body and are contained within the hems, a child resting upon the bottom of the body is supported entirely by the fabric and there is no possibility of the child coming in contact with or resting upon the frame.

The outside dimensions of the body are 85 defined by the side and end bottom seams 10 and 6 and when in operative position the body is held extended by the frames and supported within the vertical planes of the sides and ends of the frames by means of the 90 hems connected to the lower angles of the body and to the upper edges of the walls thereof which hems extend outwardly from the body. The child is supported within a rectangular body, the side walls and bottom 95 of which are formed of a single thickness of fabric which provides a smooth yielding bed for the child and within which it may be placed without danger of it falling out and which device may be hung in any place 100 desired.

Because of its construction the device is particularly adapted as a bed for small babies, which may be used by mothers in automobiles to be taken with them when 105 going upon picnics or other excursions, the device being easy to carry and readily suspended from the automobile top or from the limbs of a tree.

This device is also particularly adapted 110 for use in infants' hospitals where individual beds are required and where sanitary conditions are most essential. By reason of its construction the device may be very quickly taken apart and the fabric washed 115 whenever necessary.

Obviously, any suitable fabric may be used for the body of the device and changes may be made in the construction within the scope of the appended claims without departing from the spirit of the invention, and I do not therefore limit myself to the particular construction shown.

Having thus fully described my invention, what I claim is:

1. In a device of the character described, the combination of a fabric body having sides and a bottom, a frame for holding the upper edges of the sides in extended position, hems connected to the body along the 130

meeting angles of the sides and bottom, and the open frame comprising a pair of side members and a pair of end members connecting the ends of the side members, said side members being engaged within said hems and lying outside the planes of the surfaces of said sides of the body.

2. A device of the character described comprising a rectangular fabric body, a rectangular top frame for the upper edge of the body, an open rectangular bottom frame of greater length and width than the length and width of the body, and means engaging the frame and connecting the same to the body along the meeting angles between the sides and ends of the body and the bottom thereof, whereby said bottom is held extended by said bottom frame and supported therein out of contact therewith.

10 3. A device of the character described comprising a rectangular fabric body having hems along the upper edge of the body, and hems connected to the body along the meeting angles of the sides and bottom of the body, means secured to the upper portion of the body to hold the same in suspended position, an open rectangular frame engaged in the hems on the upper edge of the body, and an open rectangular bottom frame engaged in the lower hems, said bottom frame being of greater length and width than the length and width of said bottom

15

20

25

30

to support the bottom within the frame out of contact therewith.

4. A device of the character described, comprising a rectangular fabric body, outstanding hems extending along the upper edge of the body, outstanding hems connected to the body at the meeting angles of the sides and bottom and the ends and bottom, and open rectangular frames detachably engaged with said hems, said frames being of greater length and width than the length and width of the body to suspend the body therein out of contact therewith. 45

5. In a device of the character described, the combination of a rectangular fabric body formed with outstanding hems along the upper and lower angles of the body, said hems being open at their ends at the corners of the body and separate open rectangular frames of greater length and width than the length and width of the body and engaged in said hems to suspend the body within the frame out of contact therewith, said frames being formed in detachable sections for removal through the open ends of the hems. 50 55

In testimony whereof I affix my signature in the presence of two witnesses.

ERNA M. STEPKE.
